UNITED STATES PATENT OFFICE

158,860

CASE FOR TRANSFERS OR THE LIKE

Nelson Jardine, Hamilton, Ontario, Canada

Application November 23, 1949, Serial No. 6,209

Term of patent 14 years

(Cl. D87—3)

To all whom it may concern:

Be it known that I, Nelson Jardine, a citizen of Canada, residing at Hamilton, in the county of Wentworth and Province of Ontario, Canada, have invented a new, original, and ornamental Design for a Case for Transfers or the Like, of which the following is a specification, reference being made to the accompanying drawing, forming part thereof, and in which:

I claim:

The ornamental design for a case for transfers or the like, as shown.

NELSON JARDINE.
